UNITED STATES PATENT OFFICE.

ALBERT J. PATTON, OF LANSING, MICHIGAN, ASSIGNOR TO E. BEMENT'S SONS, OF LANSING, MICHIGAN, A CORPORATION.

WEEDER-TOOTH.

SPECIFICATION forming part of Letters Patent No. 738,477, dated September 8, 1903.

Application filed July 23, 1902. Serial No. 116,637. (No model.)

To all whom it may concern:

Be it known that I, ALBERT J. PATTON, a citizen of the United States, residing at Lansing, in the county of Ingham and State of Michigan, have invented certain new and useful Improvements in Weeder-Teeth, of which the following is a specification.

This invention relates to an improvement in Weeder-Teeth and to the fastening means employed to secure the same to the tooth-bar.

One of the objects of my invention is to provide a weeder-tooth which shall be sufficiently elastic to allow of its use without injury to the growing crops and which will be withal so constructed that it will be stiff enough to prevent any side twisting.

A further object of my invention is to provide a simple and efficient means for securing the weeder-tooth to the tooth-bar.

In the accompanying drawings, wherein a preferable embodiment of my invention is shown and wherein like numerals of reference refer to similar views in the several parts, Figure 1 is a perspective view of my improved weeder-tooth secured to the tooth-bar. Fig. 2 is a rear elevation of the same. Fig. 3 is a transverse section of the tooth-bar, showing the weeder-tooth and the means employed to secure the same in side elevation. Fig. 4 is a bottom plan view of the tooth-bar with the tooth secured thereto, and Fig. 5 is an enlarged view of the upper part of Fig. 3.

Referring now more particularly to the drawings, B indicates the tooth-bar, preferably formed of angle-iron, to which the weeder-tooth C is adapted to be secured. The weeder-tooth C is preferably constructed of two rods of steel having their lower ends welded together and drawn out to a point. The upper free ends of the tooth C are formed with the downwardly-bent portion c'. The tooth-bar B is provided at the point where it is desired to secure the weeder-tooth with two apertures b b', which are adapted to receive the free ends of the weeder-tooth C. A third aperture is formed in the tooth-bar between the openings b b', but nearer the bottom of the tooth-bar. This opening is designed to receive the bolt used to secure the clip which fastens the tooth-bar, as will be hereinafter more particularly set forth. To secure the

tooth C to the tooth-bar B, I employ a clip D, fastening-bolt A, and nut E. The clip D is adapted to stand astride the bent portions c' of the tooth C after they have been inserted 55 in the holes b b' of the tooth-bar B. The clip D is constructed with a central aperture adapted to loosely receive the end of the bolt A and at each side of said aperture with grooved portions d, adapted to fit over the 60 bent portions c' of the tooth C.

From the above description of the parts it will be seen that to secure the tooth to the tooth-bar it is only necessary to insert the free ends of the tooth C in the apertures b and 65 b' of the tooth-bar, so that the bent-over portions c' of the tooth will lie along the front edge of the tooth-bar, place the locking-bolt A in the tooth-bar from the rear side with its end projecting between the bent-over portion 70 c' of the tooth C, slip the clip D on the projecting end of the bolt A, and by means of the nut E, secured on the end of the bolt A, advance the clip D until the bent-over portions c' of the tooth C are clamped firmly between said clip D and the front edge of the 75 tooth-bar B.

In manufacturing my improved weeder-tooth I may employ either one of two methods—namely, I may make the tooth of two 80 separate rods by welding them at one end and drawing that end into a point, or I may make the tooth out of a single rod by taking a rod of about twice the length which it is desired the tooth should be, bending it at its center, 85 welding the two parts together for a short distance above the bend, and drawing out a point at the bend.

I do not desire to limit myself to the precise form and construction shown in the drawings, as it is obvious that many minor changes might be made thereto without departing in the least from the spirit of the invention.

Having thus described the invention, what is claimed as new, and desired to be secured 95 by Letters Patent, is—

1. A weeder-tooth consisting of an upper portion of two separated rods and a lower portion of a single rod drawn out to a point.
2. A weeder-tooth consisting of two rods 100 separated at their upper ends and connected at their lower ends to form a point.

3. In a weeder, the combination with a tooth-bar, of a weeder-tooth consisting of two rods separated at their upper ends and connected at their lower ends to form a point, and means for attaching said tooth to the tooth-bar.
4. In a weeder, the combination with a tooth-bar, of a weeder-tooth consisting of two rods separated at their upper ends and connected at their lower end to form a point, and a clip 10 for attaching the upper separated ends of the tooth to the tooth-bar.
5. In a weeder, the combination with a tooth-bar provided with apertures, of a weeder-tooth consisting of two rods separated at their upper ends and connected at their lower ends to form a point, the upper separated ends of the tooth engaging the apertures in said tooth-bar, and means for attaching the tooth to the tooth-bar.
- 20 6. In a weeder, the combination with a tooth-bar provided with apertures, of a weeder-tooth consisting of two rods separated at their upper ends and connected at their lower ends to form a point, the upper separated ends of the tooth engaging the apertures in said tooth-bar, and a clip for securing the tooth to the tooth-bar.
7. In a weeder, the combination with a tooth-bar provided with apertures, of a weeder-tooth consisting of two rods separated at their upper ends and connected at their lower ends to form a point, the upper separated ends of said rods engaging the apertures in said tooth-bar, a clip fitting over the upper separated 25 ends of the tooth, a bolt passing through the tooth-bar and said clip, and a nut on the end of said bolt.
8. In a weeder, the combination with a tooth-bar provided with apertures, of a weeder-tooth consisting of two bars separated at their upper ends and connected at their lower ends to form a point, and having said upper ends bent at an angle to the adjacent portions of the tooth, the upper separated ends of said tooth 30 engaging the apertures in said tooth-bar, and means for clamping the bent portions of the tooth and the tooth-bar together.
9. In a weeder, the combination with a tooth-bar provided with apertures, of a weeder-tooth consisting of two bars separated at their upper ends and connected at their lower ends to form a point, and having said upper ends bent at an angle to the adjacent portions of the tooth, the upper separated ends of said tooth 35 45 engaging the apertures in said tooth-bar, and means for attaching the tooth to the tooth-bar together.
- 50 10. In a weeder, the combination with a tooth-bar provided with apertures, of a weeder-tooth consisting of two bars separated at their upper ends and connected at their lower ends to form a point, and having said upper ends bent at an angle to the adjacent portions of the tooth, the upper separated ends of said tooth 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810
- tooth consisting of two bars, separated at their upper ends and connected at their lower ends to form a point, and having said upper ends bent at an angle to the adjacent portions of the tooth, the upper separated ends of said tooth engaging the apertures in said tooth-bar, a clip fitting over the bent ends of the tooth, a bolt passing through the tooth-bar and said clip and a nut on the end of said bolt.
11. In a weeder, the combination with a tooth-bar provided with apertures, of a weeder-tooth consisting of two bars separated at their upper ends and connected at their lower ends to form a point, the upper separated ends of said tooth engaging the apertures in said tooth-bar, a clip provided with a centrally-located aperture and with grooves at its ends engaging the upper separated ends of the tooth, a bolt passing through the tooth-bar and the aperture in the clip, and a nut on the end of said bolt.
12. In a weeder, the combination with a tooth-bar provided with apertures, of a weeder-tooth consisting of two bars separated at their upper ends and connected at their lower ends to form a point, and having said upper ends bent at an angle to the adjacent portions of the tooth, the upper separated ends of said tooth engaging the apertures in said tooth-bar, a clip provided with a centrally-located aperture and with grooves at its ends fitting over the bent portions of the tooth, a bolt passing through the tooth-bar and the aperture in the clip, and a nut on the end of the bolt.
13. In a weeder, the combination with a tooth-bar provided with apertures, of a weeder-tooth formed with two rods separated at their upper extremities, the upper separated ends of said tooth engaging the apertures in said tooth-bar, and a clip for securing the upper separated ends of the tooth to the tooth-bar.
14. In a weeder, the combination with a tooth-bar provided with apertures, of a weeder-tooth formed of two rods separated at their upper ends, and having said upper ends bent at an angle to the adjacent portions of the tooth, the upper separated ends of said tooth engaging the apertures in said tooth-bar, and a clip for clamping the bent portions of the tooth to the tooth-bar.
- In testimony whereof I affix my signature in presence of two witnesses.
- ALBERT J. PATTON.
